(57) **CLAIM**

The ornamental design for a cover for an air tank filler valve as shown and described.

DESCRIPTION

FIG. 1 is a perspective view showing my new design for a cover for an air tank filler valve.

FIG. 2 is a front view of the cover of FIG. 1.

FIG. 3 is a rear view of the cover of FIG. 1.

FIG. 4 is a right side elevational view of the cover of FIG. 1.

FIG. 5 is a left side elevational view of the cover of FIG. 1.

FIG. 6 is a bottom plan view of the cover of FIG. 1; and, FIG. 7 is a top plan view of the cover of FIG. 1.

Broken lines indicate unclaimed subject matter. Embodiments of my new design are not limited to any specific size and may be scaled larger or smaller. Embodiments of my new design do not require any specific orientation. Rather, the designations of front, rear, right, left, bottom, and top are arbitrary and are for illustration purposes only.
